UNITED STATES PATENT OFFICE

2,536,700

FUEL MIXER FOR INTERNAL-COMBUSTION ENGINES

Andrew Craig Russell, Shawnee, Okla.

Application January 2, 1948, Serial No. 195

1 Claim. (Cl. 261—50)

1

This invention relates to the automotive field, and particularly to internal combustion engines, the primary object being to provide a carburetor operable automatically and entirely through the suction created by the internal combustion engine at the intake manifold thereof to which the carburetor is attached.

An important object of this invention is the provision of a fuel mixer for internal combustion engines having an air inlet port and an outlet opening communicating with the intake manifold of the engine, said outlet port being placed into communication with the fuel bowl of the carburetor through the medium of a vertical tube having its lowermost end projecting into the fuel within the bowl, said tube being provided with a plurality of passages in register with the air intake port and so disposed as to direct air upwardly in the tube thereby creating a suction at the level of fuel within the tube.

Another important object of this invention is the provision of a fuel mixer for internal combustion engines having the aforesaid vertical tubular member and a restricted passage within said member disposed between the above mentioned passages and the level of fuel within the tubular member whereby to increase the amount of suction at said level of fuel.

A further object of this invention is the provision of a sectional partition between a pair of compartments formed in the carburetor housing, one of said sections being freely reciprocable within the housing to and from a position substantially closing an opening between said compartments, said one section being actuated entirely by the suction created by the internal combustion engine with which the mixer is used.

A further object of this invention is to provide a carburetor of the aforementioned character wherein one of the sections of the partition is shiftable vertically within the housing by a manually rotatable shaft extending to the exterior of said housing whereby the opening between the said pair of compartments may be increased or decreased at will.

A still further object of this invention is the provision of a fuel mixer for internal combustion engines having a removable plug mounted in the lowermost end of the vertical tubular member for controlling the amount of fuel flowing into said tubular member.

Another object of this invention is the provision of a fuel mixer for internal combustion engines having a pipe telescoped within the above mentioned tubular member and commun-

cating with the plug at the lowermost end thereof for receiving fuel from the bowl of the housing directly when air is forced into the tubular member and toward the uppermost end thereof.

Another very important object of this invention is the provision of a fuel mixer for internal combustion engines wherein the above mentioned plurality of passages within the vertical tubular member are not only disposed at an angle with respect to the longitudinal axis of the tubular member but at an angle to its transverse axis whereby to create a whirl in the tubular member as the air enters thereinto.

15 Another important object of this invention is the provision of a fuel mixer for internal combustion engines having the above mentioned sectional partition wherein the said freely shiftable section of such partition has a plurality of angularly disposed radial vanes defining perforations therein whereby to create a whirl in the air passing through such perforations that is opposite in direction to the whirl within the tubular member thereby creating a turbulence at the uppermost end of said tubular member.

20 Other objects will be made clear or become apparent during the course of the following specification, reference being had to the accompanying drawings, wherein:

25 Figure 1 is a substantially central vertical cross sectional view taken through a fuel mixer for internal combustion engines made in accordance with the present invention.

30 Fig. 2 is a fragmentary cross sectional view taken on line II—II of Fig. 1 looking in the direction of the arrows.

35 Fig. 3 is a transverse cross sectional view taken on line III—III of Fig. 1.

40 Fig. 4 is an enlarged fragmentary detailed cross sectional view taken on line IV—IV of Fig. 1.

45 Fig. 5 is a detailed elevational view showing the locking means for the manually operable shaft.

50 Fig. 6 is a fragmentary cross sectional view similar to that shown in Fig. 1 but illustrating a modified form of the present invention; and

55 Fig. 7 is a fragmentary cross sectional view similar to that illustrated in Fig. 1, showing another modified form of the present invention.

The fuel mixer illustrated in Figs. 1 to 5 inclusive of the drawings, includes a housing broadly designated by the numeral 10 that includes three hollow sections 12, 14 and 16 respectively. The sections 12 and 14 are joined

together through the medium of bolts or the like 18 while the section 16 depends from section 14 and is removably joined thereto by means of a number of bolts or the like 20.

A portion of the center section 14 forms a first compartment 22 having an air inlet port 24 communicating therewith.

A butterfly valve 26 of conventional character for choking purposes, is mounted within the compartment 22 and movable manually through structure not shown, to and from a position closing the air inlet port 24.

Another compartment 28 is formed in the housing 10 through the section 12 thereof and a portion of the section 14. These compartments 22 and 28 are interconnected by a passageway 30 defined by a continuous internal shoulder 32 formed in the section 14 of the housing 10.

A liquid fuel inlet port 34 formed in the section 16 of housing 10 (said section 16 forming a third compartment 36 which constitutes the fuel bowl of the mixer), has a reciprocable valve 38 mounted therein. This valve 38 is secured to a bracket 40 pivotally mounted within the compartment 36 and having a conventional float 44 mounted on one end thereof. It is thus seen that the float 44 and valve 38 operate to maintain the liquid fuel within compartment 36 at a predetermined level, said fuel flowing from a suitable source not shown through a conduit 46 communicating with inlet opening 34.

A hole 48 is formed in the normally bottom wall of the section 14 of housing 10 for receiving a vertical tubular member 50. This member 50 has an annular external flange 52 formed thereon intermediate its ends, this flange 52 underlying the bottom wall of the section 16 and being secured thereto through the medium of screws or the like 54.

As clearly illustrated in Figs. 1 and 2, the lowermost end of the tubular member 50 extends into the compartment 36 and into the fuel therein. The uppermost end of member 50 extends upwardly through the compartment 22 and terminates at its uppermost end within the compartment 28 of housing 10.

As shown in Figs. 1 and 4, a plurality of passages 56 are formed in the tubular member 50 and disposed to place the compartment 22 of housing 10 into communication with the interior of member 50. Fig. 1 illustrates the way in which these passages 56 are formed to extend at an angle to the longitudinal axis of member 50 with the innermost ends thereof closer to the uppermost end of member 50 than the outermost ends of passages 56. In addition to these passages 56 being disposed at such angle, they are also formed at an angle to the transverse axis of member 50. In other words, each of the passages 56 are inclined vertically and disposed tangentially to the tubular member 50, the latter disposition being clearly shown in Fig. 4.

A partition between the compartments 22 and 28 of the housing 10 comprises a pair of sections 58 and 60. The section 60 is disposed within the compartment 22 of housing 10 and is threadably mounted for vertical reciprocation upon the tubular member 50. A cavity 62 formed in the member 60 at its lowermost end circumscribes and provides clearance for the passages 56 within the member 50. External threads 64 formed on the member 60, mesh with screw threads 66 on a transverse shaft 68 mounted within the section 14 of housing 10.

A cavity 70 rotatably receives the innermost

end of this shaft 68 while the opposite end thereof passes through an opening 72 in the opposite wall of the housing 10 and terminates exteriorly of said housing 10.

A small disk 74 secured to the outermost end of the shaft 68 permits manual rotation of said shaft 68, which rotation causes vertical reciprocation of the section 60 upon the member 50. A short projection 76 extending from the housing 10 threadably receives a pin 78. This pin 78 passes through the free ends of a U-shaped bracket 80, said bracket 80 circumscribing the shaft 68 between disk 74 and the housing 10. Thus as the shaft 68 is rotated to adjust the section 60 to the desired position, shaft 68 may be locked against rotation through the medium of screw 78 and the clamp 80.

A shoulder 82 formed on the shaft 68 abuts the clamp 80 and shaft 68 is thereby held against outward movement from housing 10. The section 58 has a hub 84 slidably circumscribing the member 50 from which hub 84 extends radially a plurality of vanes 86. These vanes 86 define a number of perforations 88 in the section 58 and are slightly inclined as indicated in Fig. 3. This section 58 normally rests upon the section 60 and is disposed within the passage 30 between the compartments 22 and 28 of housing 10. When in said normal position the section 58 substantially closes said passage 30, there being only a slight space between the periphery of section 58 and the shoulder 32 of housing 10.

A tapered pin 90 mounted within a plug 92 which in turn is threaded into the lowermost end 35 of the tubular member 50, serves as a valve to prevent passage of fluid from compartment 36 to the tubular member 50 when said pin 90 is at the lowermost end of its path of travel. The lowermost pointed end of the pin 90 rests upon 40 a flat plate 94 within the compartment 36 and this plate 94 is joined to the section 84 through the medium of a pair of posts. These posts 96 are each reciprocably mounted within openings 98 formed in the bottom wall of the section 14. 45 An internal shoulder formed in the tubular member 50 between the level of liquid fuel within compartment 36 and the passages 56 has a relatively small opening 100 formed therein.

An outlet opening 102 formed in the section 50 12 of the housing 10 in communication with the compartment 28 registers with the intake manifold of the internal combustion engine with which the mixer is to be used. A suitable passageway, not shown, between outlet opening 102 and the engine may have a conventional butterfly valve therein operably connected to an accelerator in the usual manner.

In operation, the conduit 46 is connected to a suitable source of fuel supply and float 44 operates through the valve 38 to maintain such liquid fuel at a predetermined level within the compartment or fuel bowl 36. Adjustment is made to permit entrance of enough fuel into the tubular member 50, past the valve 90 to maintain a level of fuel within such tubular member 50 when the mixer is not in use. In other words, even with the plate 94 at the lowermost end of its path of travel as determined by the section 84 resting upon the uppermost face 65 of section 60, the lowermost end of tubular member 50 being within the fuel in fuel bowl 36 there will always be a level of such fuel in member 50. As soon as the ignition system of the internal combustion engine is rendered operable 70 of section 60, the lowermost end of tubular member 50 being within the fuel in fuel bowl 36 there will always be a level of such fuel in member 50. As soon as the ignition system of the internal combustion engine is rendered operable 75 and while attempts are being made to start such

engine, there will immediately be a suction created at the intake manifold of the internal combustion engine. This suction will be transmitted through the outlet opening 102 and into compartment 28 of the housing 10. A small amount of air will be drawn into the engine from air inlet port 24, such air passing into compartment 22 through passageway 32 and thence into the compartment 28 because of the space around the section 84.

Obviously to facilitate starting, such passage of air may be eliminated by the closing of butterfly valve 28. While the engine is thus being started, the suction within compartment 28 will be transmitted into the uppermost end of the tubular member 50. This suction within tubular member 50 will draw air from the compartment 22 through passages 56. Such in-rushing air through passages 56 will be directed upwardly toward the uppermost end of the tubular member 50 thereby creating a suction above the restricted opening 100 within tubular member 50. Such suction will also be present below the restricted opening 100 but have increased intensity because of such opening 100 and this suction at the level of fuel within member 50 will draw such fuel upwardly through opening 100 and toward the uppermost end of tubular member 50. When this fuel reaches the innermost ends of the passages 56, the same will admix with air passing through such passages 56 and this admixture will be enhanced because of the whirling action of the air within tubular member 50 because of the precise disposition and angularity of passages 56 with respect to both the longitudinal and the transverse axes of tubular member 50. As the mixture of air and fuel passes upwardly and from the uppermost end of the tubular member 50, it mixes with air passing from inlet opening 24 through compartment 22, passage 32 and compartment 28 before entering the internal combustion engine through outlet port 102. After the engine starts and butterfly valve 28 is opened, more or less fuel will be allowed to pass into the engine by manipulation of the accelerator operated butterfly valve above mentioned. As such last mentioned valve is opened, a greater amount of suction is created at the outlet opening 102, this increased suction serving to draw the freely slideable section 84 upwardly upon the tubular member 50. When this section 84 rises from its normal position seated upon the section 88, air from inlet port 24 will pass into the compartment 22 and thence into compartment 28 through the perforations 88 within the section 84. This air impinging upon the angularly disposed vanes 86 of the section 84 will whirl in a direction opposite to the direction of whirl of air within the tubular member 50. When the whirling mixture of air and fuel emanating from the tubular member 50 strikes the oppositely whirling air within the compartment 28, a turbulence will be established at the uppermost end of the tubular member 50 creating a complete atomization of the fuel particles prior to the same passing through outlet port 102. It is thus seen that all air and fuel passing into the internal combustion engine will be thoroughly admixed before the same passes from housing 10 through outlet port 102, thereby causing an extremely desirable condition through fuel savings as well as increased efficiency and better performance of the internal combustion engine.

Reciprocation of the member 88 upon the tube 50 through the medium of shaft 82, will increase

or decrease the space between the periphery of member 50 and the shoulder 32 thereby adjusting the mixer for idling to the speed desired. It is also apparent that as the member 50 is reciprocated through suction of the internal combustion engine, more or less fuel will be permitted to flow into the member 50 because of the actuation of the tapered valve 90.

The modification shown in Fig. 6 is substantially the same as that just described with respect to the form illustrated in Figs. 1 to 5 inclusive, there being a housing 110 having a fuel bowl 114, an air inlet compartment 116 and a compartment 118 that communicates with an outlet opening not shown.

An elongated vertical tubular member 120 places the compartment 118 into communication with the fuel bowl 114, this member 120 having a partition formed from a pair of sections 122 and 124 in precisely the same manner as above described with respect to the modification of Figs. 1 to 5 inclusive. The partition, i. e. sections 122 and 124 are adjusted in the same manner through the medium of a rotatable shaft 126 having external threads thereon in mesh with threads 128 of the section 124. A level of fuel is maintained within the bowl 114 and thereby within the tubular member 20 through the medium of a float 130 operably connected to a valve 132 reciprocably mounted within a fuel inlet port 134. A plurality of passages 136 are formed in the tubular member 120 in the same manner as passages 56 as illustrated in Figs. 1 and 4. The tapered valve 90, the plate 94 and the posts 96 are entirely eliminated in the modification shown in Fig. 6 and in lieu thereof a removable plug 138 having an opening 140 therethrough is threaded into the lowermost end of the tubular member 120. This plug 138 is rendered easily removable by a drain plug 142 disposed within the fuel bowl 114 in direct underlying relationship to the perforated plug 138. Thus a constant supply of fuel is directed to the tubular member 120 dependent upon the size of the plug 138 that is used. The use of such a plug 138 eliminates the costly construction of the modification shown in Figs. 1 to 5 inclusive and obviously there are fewer operative parts likely to become maladjusted or worn through use. The use of such plug 138 has the disadvantage however, over the modification first described in that an unlimited supply of fuel to the tubular member 120 is not possible.

When the fuel mixer made in accordance with the modification shown in Fig. 6 is used for differing types of internal combustion engines, it will become necessary to change plugs 138 having openings 140 therethrough of different sizes.

The modification shown in Fig. 7 of these drawings is substantially the same as that just above described in Fig. 6 in that there is a fuel bowl 200, an air inlet compartment 202 and an outlet compartment 204. In this instance, the vertical tubular member 206 has a plug 208 threaded into its lowermost end in much the same manner as the plug 138 of the modification shown in Fig. 6. In this instance however, the plug 208 has affixed thereto a relatively small pipe 210. This pipe 210 extends into the tubular member 206 terminating therein in spaced relation to the uppermost end of member 206 and above the innermost end of angularly disposed passages 214 within tubular member 206. The plug 208 has an opening 216 formed therein

placing the pipe 210 into communication with the fuel bowl 200.

An internal shoulder 220 much like the shoulder shown in Fig. 1, defining the opening 100, supports the pipe 210 intermediate its end.

In the modification shown in Fig. 7, there is likewise a level of fuel within the pipe 210 because of the fact that tubular member 206 extends into the fuel within the bowl 200. Such fuel will pass through the opening 216 of plug 208 and into the pipe 210, there being always a constant supply of such fuel.

In operation, since passages 214 are formed in the same manner as that above described with respect to Figs. 1 and 4, air from compartment 202 will be directed upwardly toward the uppermost end of tubular member 206, thereby creating a suction within the pipe 210. Such suction at the level of fuel within the pipe 210 will cause the fuel to move upwardly and meet with whirling air at the uppermost end of pipe 210. The mixture of air and fuel will then pass upwardly through tubular member 206 to mix with whirling air at the uppermost end of this last mentioned member in the same manner as above described.

Having thus described my invention, what I claim as new and desire to secure by Letters Patent is:

In a fuel mixer for internal combustion engines, a hollow, compartmental housing having an air inlet port communicating with one of its compartments, an outlet opening in register with a second of its compartments, and a valved inlet port for liquid fuel to be mixed with air registering with a third of its compartments; means in said third compartment and operably connected with the valve of said fuel inlet port for maintaining the fuel at a predetermined level in the third compartment; and a vertical, tubular member having one end thereof within the fuel in said third compartment and its opposite end terminating in said second compartment, said member having a plurality of passages formed therein intermediate the ends thereof

to place the interior of the member into direct communication with said one compartment of the housing, said passages being disposed to direct air from the one compartment toward said opposite end of the tubular member whereby to create a suction at the level of fuel in the tubular member as the air is forced from the opposite end of the tubular member through said outlet opening, said housing having a passageway interconnecting the one compartment and the second compartment thereof and a sectional partition shiftably mounted therein, one of the sections of the partition being freely movable in the housing and normally supported by the other section, said one section being disposed within the passageway in spaced relation to the walls of the housing forming the passageway when in said normal position, said other section being in screw-threaded engagement with said tubular member and having manually-operable actuating means for varying the size of said space when the one section is in said normal position, said actuating means including a shaft rotatably mounted in said housing and extending outwardly therefrom, said shaft being operably joined to said other section for rotating the same on the tubular member and having releasable means on the exterior of said housing for locking the same against rotation.
